ROLF STÖHR, OF BERLIN-WILMERSDORF, GERMANY

VALVE LIFTER FOR BATHS, LAVATORIES, AND THE LIKE

Application filed October 12, 1929, Serial No. 399,276, and in Germany October 18, 1928.

The invention relates to improvements in valve lifters to be mounted in the waste outlet of baths, lavatories etc. The object of the invention is to provide for an arrangement 5 of the valve lifter by which it is made possible to withdraw the latter, at any time and without difficulty, from the waste pipe or outlet so that both the valve lifter and the waste pipe or outlet always subject to pollution can 10 be cleaned, when necessary.

The invention consists in that the lifting arm extending beneath the waste valve is linked to the bottom end of the rod inserted in the waste or overflow tube in such a way 15 that the lifting arm is susceptible of being angularly displaced in the plane going through the said rod and the waste valve and that the joint can be fixed within the bent portion of the overflow tube or canal when the 20 elements of the rod gear form a knee. This arrangement allows of the lifting gear being inserted in the overflow tube as a complete unit in operative condition with freely movable joint by any person without special knowledge, as the lower lifting arm, freely rocking when being inserted, is able to follow the 25 bottom curvature of the overflow tube on account of its particular design. When the lowest point of this tube or canal has been 30 reached, the elements of the rod gear occupy the knee-like position required for fixing the joint automatically. After the joint has been fixed all elements of the same rod gear form a rigid unit and are susceptible of moving in parallel directions when the valve is 35 being operated.

According to the invention the joint is fixed by a lug disposed on one of the elements of the joint which lug is in engagement with a 40 recess of the other element of the joint when these two elements are forming a knee. This lug intended for fixing the joint preferably consists in a spindle guided within the lifting rod which first enters by its own weight or by being pushed, the opposite recess of the 45 other part of the joint in the knee-like position of the latter.

The spindle fixing the joint preferably extends through the handle of the lifting rod so 50 that the joint may be disengaged by the spin-

dle being lifted from without. The valve lifter designed according to the present invention can therefore be inserted and withdrawn as a complete unit ready for use in a convenient and easy way.

The accompanying drawings represent an instance of execution of the present invention.

Fig. 1 shows a valve lifter inserted in the overflow canal of a lavatory in natural size, the lavatory being represented partly and in 60 section with the disc valve.

Fig. 2 is a longitudinal sectional view of the head and the bottom joint part of the valve lifter, the joint having been fixed.

Fig. 3 is a side elevation, partly in vertical 65 section of the same parts of the valve lifter in their position corresponding to Fig. 1, the joint fixed being shown laterally.

Fig. 4 shows the lifting rod gear, partly in section, with the joint having been loosened.

The joint connecting both main parts of the valve lifter consists of the fork head nut 2 which is screwed on the hollow rod 5 and, on the other hand, of the arm 4 linked to the fork head 1 by means of the pin 3 secured 75 in its position by the washer 6 and the split pin 7.

At its end inserted in the fork head 1 the arm 4 is provided with a recess 8 into which the bottom end of the sleeve 39 screwed on 80 the spindle 9 and secured in its position by collar 38 drops by its own weight or is pushed as soon as the arm 4 has occupied its normal position after the valve lifter unit having been brought into the overflow canal 24. In 85 this way the joint 1 has been fixed.

The spindle 9 extends outwards through the handle 16 of the valve lifter. Its outer end carries the screw 10 screwed-in which is 90 designed in such a manner that when it is seized and the spindle 9 lifted the joint 1 is loosened. Within the hollow rod 5 the spindle 9 is guided at first in a lengthwise direction and displaceable longitudinally and, as soon as the stop formed by slot 11 and pin 12 is reached, also angularly; the spindle 9 having been pulled out as far as the stop at the pin 12 and then turned, the pin 12 gets into the grooves 41 arranged at the lower 95 end of and at a right angle to the slot 11 in

the same height. Now the spindle 9 is secured against unintentional dropping into its primitive position while the rod gear is being withdrawn.

- 5 The pin 12 secured by washer 6 and split pin 7 and provided in the hollow rod 5 is intended for four different purposes; firstly for limiting the lift of the spindle, secondly for preventing the spindle from being pulled 10 out, thirdly for being the seat of the spindle with loosened joint (viz, especially for withdrawing the valve lifter) and fourthly for preventing the lower part of the joint from being turned sidewise to which end the pin 15 12 also goes through the sleeve 13 of the lifter head and slides up and down, while the valve is being opened and closed respectively, in the slots 40 of the sleeve 13.

At its top the hollow rod 5 is provided with 20 a collar 14 which bears against the lower smooth part of a corresponding bore of the sleeve 15. The upper part of this bore is provided with winding, into which the handle 16 is screwed. The latter is secured against 25 being detached unintentionally by a small screw 17. The sleeve 15 is inserted in the sleeve 13 and displaceable in the latter in a lengthwise direction. At its lower end it is provided with four projections 18 extending 30 into longitudinal grooves 42 of the sleeve 13. These grooves run into a circular 19 of the same depth arranged at the end of the sleeve 13 so that the projections 18 having got into 35 this circular groove after the valve lifting rod gear having been raised, a simple turn of the handle 16 permits of the whole lifting rod gear now secured in its position being fixed in its lifted condition. The disc valve arranged at the lowest point of the lavatory 40 (25, Fig. 1) is now in its opened position. According to the present invention, the projections 18 of the sleeve 15, displaced 90° in 45 respect to each other, are covered up and vertically slide in the corresponding grooves 42 of the lifter head shell 43. Against dirt while being used and against being drawn out, the sleeve 15 is secured by the cap 20 screwed upon the lifter head shell 43. When 50 the valve is to be closed, the handle 16 is turned through an angle of 90° regardless of the direction. Now the sleeve 15 will drop as far as its lowest position under the influence of its own weight and of that of the 55 whole lower part of the lifting rod gear and being uniformly guided in the four grooves, viz, the valve 25 will be closed.

The lifter head shell 43 and the whole lifter head respectively are inserted in the plate 21, which preferably is at the same time the 60 strainer of the overflow canal 24, and connected to this plate by the nut 22 with washer 23. As to the plate 21, it is fastened sufficiently safely to the lavatory 33 by any suitable means, not represented in the drawings, 65 but allowing to take off the plate 21 together

with the whole lifter head. The holes 32 shown in Fig. 2 represent the overflow slots required when the water flow is excessive while the valve is closed.

The lifter arm 4 actuating the valve and suitably designed in accordance with the invention is provided with a straight portion 26 at its end, which portion horizontally extends, when the joint is fixed, beneath the perforated disc 30 which is disposed in the waste tube 28 and forms a rigid unit with the valve spindle 27, its purpose being moreover to be a waste strainer at the same time. After adjustment, the nut 29 secures the perforated disc 30 also used as a lower guide and the spindle 27, to which both the valve disc 25 is screwed, against the valve being angularly displaced and misplaced.

With its flange 34 the waste tube 28 is inserted in a gasket 31 and it is provided with a seat 36 corresponding to the jointing surface 35 of the valve disc 25.

Preferably the disc valve 25 is provided with three guide ribs 37 extending into the waste tube 28 and sliding along the inner wall surface of the latter which ribs are intended for guiding the valve. The space between these ribs and the shank of the valve disc is preferably recessed which arrangement substantially increases the speed of flow and so causes a quicker evacuation of the lavatory.

The valve lifter is mounted as follows:

At first the joint 1 of the rod gear is loosened by the spindle 9 being raised, so that the lifting arm 4 occupies the position shown in Fig. 4. Preferably the spindle 9 is not secured in its raised position by a turn while the lifter is being inserted, but the spindle 9 is allowed to bear against the portion of the lifting arm 4 which first moves within the fork of the joint, the spindle 9 being pressed down by its own weight. Thereupon the rod gear forming a unit ready for use is introduced into the overflow canal which causes the lifter arm 4 to occupy the position shown in Fig. 3 as soon as it gets into the bent portion of the overflow canal 24. After this position having been arrived at in the lowest knee-like portion of the overflow canal the recess 8 of the lifter arm 4 is opposed to the end of the sleeve 39 of the end of the spindle 9 so that, under the weight of the spindle or by being pushed, the said end penetrates into the recess 8. In this way the joint has been fixed and now the lifter arm 4 occupies a position in which its straight free end 26 extends into the waste tube 28. The valve unit composed of the valve disc 25, the valve spindle 27, the collar 29 and the waste strainer 30 serving as a central guide is now introduced from without into the waste tube 28 and rests, when closed, on the seat 36. As the lifter rod gear was introduced, also the clamping springs suitably 130

fastened to the plate 21 spread out against the inner wall surface of the overflow channel so that the valve lift is sufficiently prevented from being pulled out too easily and 5 without intention, apart from the fact that, according to the invention, the valve lifter gear rod cannot be withdrawn unless the joint between the rod gear and the lifter arm has been loosened previously.

10 The valve is opened by the knob handle 16 fastened to the top of the sleeve 15 being raised and for fixing the valve in its opened position a slight turn of the knob handle is sufficient. As according to the invention the 15 whole lifter unit is guided and suspended within the sleeve 15 and thus all parts of the same partake of the lifting movement when the sleeve 15 is being lifted by the knob handle 16, also the valve is lifted at the same 20 time; while the rod gear is raised for the purpose of the valve being opened or lowered for the closure of the latter, all parts of the valve rod gear move in directions parallel to each other.

25 The valve is closed by a further slight turn of the knob handle 16 by which movement the projections 18 extending from the sleeve 15 are caused to coincide with the grooves 42 arranged within the lifter head shell 43 and to slide down in and guided by these grooves. As the lifter rod gear positively follows the descending movement during the closure, now the valve will be closed in the waste tube, all parts of the lifter rod gear 30 likewise moving in directions parallel to each other.

In case the overflow canal is to be cleaned, the joint is loosened by the spindle 9 being pulled out whereupon the valve lifter together with the strainer plate 21 fastened to it may be withdrawn as a unit from the overflow canal. Before the valve lifter is withdrawn the spindle 9 should preferably be lifted as far as the stop and then secured in 45 its raised position by a slight turn so that both hands can be used for withdrawing the valve lifter.

For the purpose of cleaning the waste tube 28 and the waste strainer 30 forming a rigid 50 unit with the disc valve, it is recommendable to take out the valve in its open position whereupon it is readily possible to clean the waste tube as well as the valve itself.

55 The valve is inserted again without any difficulty regardless of whether the valve lifter has been introduced previously or is mounted afterwards.

What I claim as my invention, and desire 60 to secure by Letters Patent, is—

1. A valve lifter for baths, lavatories and the like, consisting of a lifting rod arranged within the overflow canal, a lifting arm pivotally linked to the bottom end of said lifting 65 rod and susceptible of being fixed to the said

rod in an angular position by means of a stop member displaceable in the lifting rod.

2. A valve lifter for baths, lavatories and the like, consisting of a lifting rod arranged 70 within the overflow canal, a lifting arm pivotally linked to the bottom end of said lifting rod, a recess arranged in the joint portion of the lifting arm and a lug displaceable in the lifting rod and susceptible of being slid into the said recess. 75

3. A valve lifter for baths, lavatories and the like, consisting of a lifting rod arranged 80 within the overflow canal, a lifting arm pivotally linked to the bottom end of said lifting rod, a recess arranged in the joint portion of the lifting arm and a lug displaceable in the lifting rod and susceptible of being slid into the said recess which lug is represented by a shell adjustable in height and fastened to the bottom end of a spindle guided within the 85 lifting rod.

4. A valve lifter for baths, lavatories and the like, consisting of a lifting rod arranged 90 within the overflow canal, a lifting arm pivotally linked to the bottom end of said lifting rod, a lug fixing the joint connecting the arm to the rod, a spindle guided within the lifting rod and extending outwards through the handle of the valve lifter, a sleeve rotatably mounted on the knob of the spindle and 95 a lifter head provided with notches.

In testimony whereof, I have signed my name to this specification at Berlin-Wilmersdorf, Germany, this 3rd day of October, 1929.
